UNITED STATES PATENT OFFICE.

HAROLD ROWNTREE, OF KENILWORTH, ILLINOIS.

INTERLOCKING CONTROL SYSTEM FOR ELEVATORS.

1,216,846.

Specification of Letters Patent. Patented Feb. 20, 1917.

Application filed April 8, 1914. Serial No. 830,406.

To all whom it may concern:

Be it known that I, HAROLD ROWNTREE, a citizen of the United States, residing at Kenilworth, in the county of Cook, State of Illinois, have made a certain new and useful Invention in Interlocking Control Systems for Elevators, of which the following is a specification.

This invention relates to interlocking control systems for elevators.

The object of the invention is to provide a control system for elevator interlocking mechanism which is simple and efficient and wherein control of the car movements may be effected for emergency or other purposes independently of the interlocking mechanism.

A further object is to provide a control arrangement of the nature referred to wherein when the operation of the car independently of the interlocking system is effected one or more signals are also operated to indicate such independent operation.

A further object is to provide a control and signal arrangement of the nature referred to wherein manual or other operation is necessary in order to restore the parts to their normal condition after a car is operated independently of the interlocking system.

Other objects of the invention will appear more fully hereinafter.

The invention consists substantially in the construction, combination, location and relative arrangement of parts, all as will be more fully hereinafter set forth, as shown in the accompanying drawing and finally pointed out in the appended claims.

Referring to the drawings and to the various views appearing thereon,—

Figure 1 is a view in diagram showing an arrangement of interlocking control circuit for elevators, and an auxiliary control switch to permit the operation of the car independently of the interlocking system.

Fig. 2 is a similar view showing an auxiliary control switch on the car, and also showing a contact arrangement controlled by the door or gate on the car included in the interlocking circuit system.

Fig. 3 is a similar view showing the use of a signaling system in connection with the auxiliary control.

Fig. 4 is a similar view showing an arrangement of locking relay employed in connection with my invention.

The same part is designated by the same reference numeral wherever it occurs throughout the several views.

In the operation of elevators, dumb-waiters, or the like, and in order to secure the highest degree of safety in the operation thereof, it is customary to provide an interlocking circuit system to control the hoisting motor so arranged that when any elevator shaft door is open, or when the car door or gate is open the motor control circuit is opened and the car cannot be operated until all of said doors or gates are closed. It sometimes happens, however, that in emergencies, or for special reasons, it is desirable to operate the car without closing the doors, as, for instance, where it is desired to inspect, repair or lubricate the mechanism within the elevator well and for such purpose a workman enters the well and is carried upon the roof of the car while performing his duties. In order to enable him to reach the roof of the car from any floor or landing it is necessary to open the shaft or well door and lower the car until the roof reaches a convenient point for the workman to climb onto the same through the doorway. Other exigencies also frequently arise requiring the operation of the car independently of the interlocking circuit control system.

In such cases it becomes necessary to control the car operations independently of the interlocking system. When so operated, however, it is desirable to employ a suitable signaling system in connection with the independent control to indicate when the emergency or auxiliary independent control is effected, and to provide means which require manual or special operation to restore the parts to their normal position for interlocking control. It is among the special purposes of my present invention to provide means which are simple and efficient for accomplishing these and other advantageous results.

In the drawings, reference numeral 5 designates a car, and 6 its hoisting mechanism including a motor 7. The operation of the hoisting motor may be controlled by an electric circuit, *a*, which may supply or control the supply of operating current to the motor. This circuit I will call the motor control circuit. This circuit extends throughout the length of the elevator well or shaft and is controlled in such manner that when any shaft or well door 9, or the car door 10, is

open, said circuit is opened. For instance, a contact device, indicated at 8, is employed in connection with each door 9, 10, and so arranged with reference thereto, and in the 5 motor control circuit, as to be closed when the door is closed and open when the door is opened.

With this interlocking circuit system it will be seen that when any elevator shaft 10 or well door is open or, as in Fig. 2, when the door of the elevator car is open, the hoisting motor is inoperative and remains so until all of the doors are again closed.

In order to provide for the emergency 15 or other operation of the car independently of the interlocking circuit system referred to, and in accordance with my invention, I provide an auxiliary switch 11, for supplying current to the motor independently of 20 the door controlled contacts 8. This auxiliary switch may be located at any convenient point, as, for instance, at the control board from which it may be operated by the engineer in charge of the elevator plant of 25 a building, for instance, or at the control station of a "one point" control elevator system. If desired, however, an auxiliary switch 12, having the same purpose and function, may be located on the car as indicated in Figs. 2 and 3.

With the arrangement above described, it will be seen that whenever desired or required, the control of the car operation may be taken from the interlocking system by 35 the manipulation of the auxiliary switch 11 or 12, and that when said auxiliary switch is closed the car is operated as desired independently of the interlocking circuit system.

40 In order to provide against the danger of the inadvertent operation of the car through the agency of the auxiliary switches, or either of them, and to indicate when such operation takes place, I propose, 45 in accordance with my invention, to associate a signaling system with the auxiliary control of the motor in such relation that when the motor is operated a signal, either audible or visible, is effected at any desired point. In Fig. 3, I have shown such a signal system. In this case, and as illustrative of the principles involved I provide signals 13, 14, 15, which are shown as lamps. 50 These signal devices may be located at any desired or convenient point. For instance, I have shown the device 13, located on the car, the device 14 at the station of the starter, and the device 15 at the control board. It is 55 evident, however, that a signal device may be located at any desired point. The signal devices are included in a circuit b which is normally open but is closed when the auxiliary motor control circuit is closed through the operation of the auxiliary switches 11 or 60 12. This control of the signal circuit may

be accomplished in any suitable or convenient manner. It is desirable, however, that such control be so effected as to require manual or other special manipulation to restore the hoisting motor control to the interlocking circuit system for normal operation, and consequently, in accordance with my invention, I provide means to lock the signal circuit closed whenever an auxiliary switch 11 or 12 is closed, so that, thereafter and until released by manual or other special operation, the signals continue in operation. To this end I provide a relay device which is electrically operated by the closing of an auxiliary switch 11, 12, and which includes a magnet coil 16, included in the circuit c of the auxiliary switches 11, 12. The armature 17 of this coil is movable and when attracted by the energization of the magnet, closes the signal circuit b, as clearly shown in Figs. 3 and 4. A latch device 18, engages the armature 17, when the latter is in signal circuit closing position, and locks the same in that position. This latch must be manually or otherwise released in order to restore the parts to the normal position for interlocking circuit control of the hoisting motor. In practice the relay control device for the signal circuit should be so located as to be under the supervision and control of someone other than the conductor or other attendant on the car, thereby preventing the possibility of accidents due to the conductor or car attendant rendering the interlocking control system inoperative and then restoring the same will. Therefore I find it expedient to locate the signal circuit control relay at the switch or control board, or at the "one point" control station.

It is obvious that many variations and changes in the detail of construction and arrangement might readily occur to persons skilled in the art and still fall within the spirit and scope of my invention. I do not desire, therefore, to be limited or restricted to the exact details shown and described.

But having now set forth the objects and nature of my invention, and construction and arrangements embodying the principles thereof, what I claim as new and useful and of my own invention, and desire to secure by Letters Patent is,—

1. The combination with an elevator and its hoisting motor, and an interlocking control circuit therefor, of means to render the interlocking control circuit inoperative and to independently operate the motor, a signal device made operative when the interlocking control circuit is rendered inoperative, and means to lock the signal device when operated, in an operative condition.

2. The combination with an elevator and its hoisting motor, and an interlocking control circuit therefor, of

auxiliary control circuit for the motor, a switch to control the same, and a signal device made operative when said switch is closed, and means to lock the signal device, 5 when operated, in an operative condition.

3. The combination with an elevator car, its hoisting motor, and an interlocking door controlled control circuit therefor, a signal device made operative when said switch is 10 closed, and means to lock said signal device in operation.

4. The combination with an elevator car, its hoisting motor and an interlocking door controlled control circuit therefor, of an 15 auxiliary control circuit for the motor, a signal circuit and a switch to close the auxiliary and signal circuits and to open the interlocking control circuit and means to lock the signal circuit when closed, in its 20 closed condition.

5. The combination with an elevator car, its hoisting motor and an interlocking door controlled control circuit therefor, of an auxiliary control circuit for the motor, a 25

relay device therein, a switch to close said circuit and to open said interlocking circuit, and a signal device controlled by said relay and means for locking said signal device, when operated by said relay in operative condition. 30

6. The combination with an elevator car, its hoisting motor, and an interlocking door controlled control circuit therefor, of an auxiliary control circuit for the motor, a relay in said auxiliary circuit, a switch to 35 close said auxiliary and to open said interlocking circuit, a signal device controlled by said relay, and a releasable lock for said relay.

In testimony whereof I have hereunto set 40 my hand in the presence of the subscribing witnesses, on this 6th day of April, A. D. 1914.

HAROLD ROWNTREE.
